WARP-STOP MOTION

Samuel W. La Rocque, Pawtucket, R. I.

Application March 24, 1948, Serial No. 16,871

8 Claims. (Cl. 139—353)

1

My invention relates to improvements in electric warp stop motions for use in looms equipped with mechanical side filling stop motions.

While I am aware that others have provided electric warp stop motions adapted to be used in conjunction with mechanical side filling stop motions, so far as I am aware these have only been connected to the rod for actuating the loom stopping means and have otherwise been entirely independent of the mechanical side filling stop motion and for their purpose have comprised a great multiplicity of parts. In addition, while these stop motions have theoretically functioned to stop the loom on back centre, in practice the stop motion mechanism tends to get so greasy that it will not stop the loom immediately and the loom will not become stopped until it gets to front centre. Thus, when the loom starts up again, there is not sufficient throw of the lay to give a sharp beat-up to the laid thread, resulting in the laid thread being spaced from the previously woven cloth, thereby providing a so-called light or starting mark or cracky cloth. In order to avoid this, certain weavers have attempted to urge the loom forward by hand so that it will again start up on back centre. Due, however, to the fact that the weaver has not as much strength as the power loom, this has tended to still leave a light or starting mark and cracky cloth, although the light mark is not so pronounced as it would have been otherwise. This has necessitated a certain amount of time in waste motion of the operator to move around to the front of the loom and pull the loom forward this extra amount, resulting in loss in production and increasing the cost of weaving, without thoroughly eliminating light starting marks and cracky cloth.

Objects of my invention are to improve upon the prior art structure of electric warp stop motions to overcome all of these defects.

In accordance with my invention I employ more of the parts of the mechanical side filling stop motion and I mount the magnetic switch adjacent the front of the loom instead of the centre of the loom and I mount an extra part on the knock-off lever and provide an extra hook bar projecting forwardly from the knock-off lever which may be alternately raised or lowered by the magnetic switch of the electric circuit controlled by the usual needles.

Employing my invention, I add a projection to one already existing part of the mechanical side filling stop motion and one extra hook bar and eliminate nineteen parts formerly thought neces-

sary. In applying electric warp stop motions to mechanical side filling stop motions, thereby greatly decreasing the cost of applying a warp stop motion to a mechanical side filling stop motion and greatly decreasing the cost of renewal of the various parts thereof as they wear out, as it is only necessary to replace two strong parts in place of nineteen weak ones. I realized I was able to achieve this by raising the added hook above the path of the reciprocating upper end of the knock-off lever, so that the end of the hook would be struck near the front of the lay by the advancing filling rod arm which normally strikes the upper end of the knock-off lever only when there is no filling passing over the lay and that this would still permit the side filling stop motion to function as usual and many of the same parts of the same mechanism to supplementally function as a warp stop motion in the event of breakage of the warp thread.

A further object of my invention is to provide a warp stop motion of this type which is more sensitive than former types as it has fewer parts of much less weight to actuate for its operation. 25 This substantially eliminates ends running longitudinally of the cloth due to the failure of the warp stop motion to stop immediately.

A further object of my invention is to provide a device in which the loom will always stop on back centre. While my device initially starts to stop the loom on front centre, due to the inertia of the loom or sluggishness of the stop motion mechanism due to oil being spilled thereon, in stopping it will always stop on back centre, thereby 35 providing a structure which corrects the former objections in warp stop motions of this type, i. e., the elimination of light or starting marks and cracky cloth and the elimination of the time of the operator in walking around the 40 loom and moving it by hand in an attempt to avoid these light starting marks which even then were only lessened not positively avoided, greatly increasing production of the loom and decreasing the weaving cost.

These and such other objects of my invention as may hereinafter appear will be best understood from a description of the accompanying drawings which illustrate an embodiment 50 thereof applied to a Draper single box loom equipped with a mechanical side filling brake stop motion.

Fig. 1 is a diagrammatic end elevation of the outside of a loom equipped with a mechanical side filling stop motion and a former type of

prior art warp stop motion employing a multiplicity of parts.

Fig. 2 is a diagrammatic end elevation of a loom showing the similar parts of the side filling stop motion mechanism and my improved warp stop motion mechanism.

Fig. 3 is a diagrammatic longitudinal sectional view taken through the centre of the loom looking towards the end of the loom equipped with the side filling stop motion having my invention attached, with the parts in back centre position.

Fig. 4 is an enlarged side elevational view looking towards the inside of the side wall of the loom having parts of the side filling stop motion mechanism and my invention attached, with the parts in substantially top centre position.

Fig. 5 is a side elevation generally similar to Fig. 4 with the parts moved to front centre position, and indicating how my invention functions to stop the loom.

Fig. 6 is a vertical sectional view taken along the line 6—6 of Fig. 5.

Fig. 7 is a perspective view of the improved knock-off bar I preferably employ.

In the drawings, wherein like characters of reference generally indicate like parts throughout, 11 generally indicates a Draper single box loom equipped with a mechanical side filling stop motion. Said loom 11 is provided with the frame 13, the lay 15 oscillatable in the usual manner by a crankshaft (not shown) and having suitable means, such as picker sticks (not shown) for reciprocating a shuttle 14 across said lay in the back centre position thereof.

Mechanical filling brake stop motions are old, 35 and comprise:

A filling rod 10, longitudinally mounted on the front portion of the lay 15. The centre of the lay is provided with a well 12. The shuttle 14, as it passes over the top of the lay, lays a filling thread across the lay. The filling motion prongs 16 project rearwardly from the rod 10 into the well 12. The rod 10 is reciprocated just prior to the shuttle passing over the middle of the lay, so that the prongs 16 project upwardly over the lay, as shown in dotted lines in Fig. 3, so that the shuttle 14, passing over the lay, may lay its filling thread over the well 12. After the shuttle has passed, the prongs 16 tend to drop down within the well, but are supported by the laid filling thread and cannot. The rod 10, pivotally mounted on the front of the lay, projects to the left end of the lay and terminates in a depending end or drum 18, having a tip 20 projecting downwardly and forwardly therefrom. At said left-hand end of the loom, an L-shaped block 22 is mounted on the end of the breast beam 24, and has an extension 28 projecting rearwardly therefrom below the lay, toward the centre frame bar of the loom. This has a central extension 30 projecting downwardly therefrom, having a longitudinal slot 32 therein. Said extension 30 has an upper end 34 projecting further rearwardly therefrom, and the upper portion of said extension has a longitudinal slot 36, projecting forwardly from said upper end 34, to substantially the center portion of said depending portion 30. A filling motion cam 38, having a forwardly depending upper cam surface 40, has an extension projecting downwardly therefrom, having a bolt projecting laterally therefrom, longitudinally adjustably securable within said cam slot 36, substantially adjacent the rear portion of the stroke of the lay. A knock-off lever 42 has a vertical slot 44 near the

lower end thereof, and an upper end 46, having a rounded front wall and a flat rear wall 47 normally projecting above the upper edge of the extension 28. Means are provided to adjustably join the lower end of said knock-off lever to a knock-off rod 48, which is attached to the brake lever 50, pivotally mounted on the front of the breast beam. The knock-off lever 42 is joined to the extension 30 by a bolt 52 which extends through the longitudinal slot 32 and the vertical slot 44, so that the effective operating upper end 46 thereof may be vertically and horizontally adjusted. The brake lever 50 actuates the usual band brake on the crank shaft (not shown), and has a projection contacting a projection on the power lever 54, which actuates, through mechanism not shown, the power for the loom, whether it be motor or belt.

In this mechanism, a shield plate 56, normally covering the inner portion of the extension 28, having an upper surface 58 normally flush with the upper surface 60 of said extension 28. The shield plate 56 is only raised upwardly so that its upper edge 58 will be above the upper end 46 of the knock-off lever 42, when the loom is restarted, and for this purpose a flat spring 62 is pivotally mounted on the breast beam to depend therefrom, which strikes the front arm 64 of the pivotally mounted shield lever 66, having a rear arm 68 adapted to abut the front end of the shield 56 to urge it rearwardly and upwardly as the loom stops, the power lever 54 actuating the spring 62 to a position to so move the shield outwardly. After one pick of the loom, the shield 56 drops down to a position below the then exposed upper end 46 of the knock-off lever 42.

In use, the prongs 16 retain the tip 20 in a position above the upper end 46 of the knock-off lever, but should the filling be broken, the prongs 16 will drop into the well 12, causing the tip 20 to get in the way of the upper end 46 of the knock-off lever so that the knock-off lever will pivot on its pivot bolt 52, so that the lower end thereof will pivot rearwardly, causing the knock-off rod 48 to pull the brake lever 50 rearwardly to actuate the brake and the power lever 54 rearwardly to shut off the power. The purpose of the cam 38, as explained, is to move the rod 20 to raise the prongs 16 in the manner explained only while the shuttle 14 passes over the well 12 and under the prongs 16.

Both the prior art warp stop mechanisms and my improved warp stop mechanism comprise electrically operated warp stop mechanisms, functioning through the knock-off lever rod 48 to actuate the brake and power levers 50 and 54. Both mechanisms are actuated through means of drop wire needles 70 individually mounted on each warp thread 72, and on an insulated needle supporting rod 74. Each needle 70 has a hollow cut-away upper portion 76, terminating in a notch 78, and having a downwardly inclined surface 80, adjacent to such notch. The threads 72 extend through suitable holes 84 substantially centrally of the needles, which in the embodiments shown comprise the upper ends 86 of slots 88, formed in the lower ends of said needles. An electric circuit has one terminal 90 connected to a positive pin contact 92, and the opposite terminal 94 connected to another ground rod contact 96. When a needle 70 drops, therefore, the pin contact 92 contacts the end of the notch 78, and the ground contact 96 contacts the inclined portion 80 of the needle to complete a circuit through the needle

70 and said contacts. The terminal 90 and terminal 94 are connected respectively to the ends of a solenoid coil 98, which has a solenoid rod reciprocally mounted within said coil or, as shown, a pivotable switch arm.

The solenoid coil 98 may actuate any suitable type of a switch whether the switch arm be mounted on a movable solenoid rod to provide a direct solenoid or whether the switch arm comprise a portion of a magnetic switch actuated by the solenoid, comprising the pivotal switch arm 91 pivotally mounted as at 93 on the coil box 95, having an inner end 97 normally raised above the upper end of the metal magnetizable solenoid core 99 and adapted on energization of said core 99 on passage of current through the coil 98 to be depressed into contact therewith, thereby providing a magnetic switch and raising the free end 101 of said arm 91. Any suitable source of electricity may be employed to energize the coil 98, and inasmuch as the showing in Fig. 3 is largely diagrammatic, I have illustrated it therein as comprising a storage battery 103 in the plus line connecting the contact 90 with the solenoid coil 98.

In the prior art, as shown in Figure 1, said solenoid coil 98 was mounted on a center bar 100 of the loom frame 13, and said solenoid rod or switch arm 91 had an end 101 projecting forwardly therefrom. A knock-off link 102 was pivotally mounted on a casting 104, mounted on a frame crossbar 106, so as to pivot forwardly and backwardly thereon. The upper end of said knock-off link 102 had a knock-off arm 108, pivotally mounted thereon, so as to project forwardly therefrom. The rear end of the lay was provided with a buffer pad 110. The front end of the knock-off arm 108 was provided with a spread-open end 112, adapted to be raised to hit the buffer pad 110. When a warp thread 72 broke and the circuit 90-94 was energized, the solenoid coil 98 and core 99 were energized to depress the inner end 97 of the switch arm 91, causing the free end 101, projecting forwardly therefrom, to be simultaneously raised. This was connected by the rod 114 to a point on the knock-off arm 108, adjacent to the pivot thereof to raise said arm 108 to a position in line with the buffer pad 110. As the lay continued its rearward stroke, the buffer pad 110 met the end 112 and the knock-off arm 108 pivoted the knock-off link 102 rearwardly. The knock-off link 102 was suitably connected to a continuation 116 of the knock-off rod 48, causing rearward movement thereof to actuate successively the brake and power levers 50 and 54, in the manner explained.

With my invention I eliminate the extension 116, the point of connection 120, the link 102, its pivot rod 122, the knock-off arm 108, its pivot rod 124, and the buffer pad 110.

My invention comprises making the electrical warp stop connection more of an integral part of the side filling stop motion, so as to utilize more of the parts thereof. For this purpose I merely provide a pivot pin 128, projecting laterally from near the upper end of the knock-off lever 42, and I provide a hooked bar 130 adapted to project forwardly from near the upper end 46 of said lever. Said bar 130 is provided with a pivot hole 132 near the rear end thereof, to receive the pivot pin 128. The front end of said bar 130 is provided with the upwardly-projecting hook 134, having a flat rear surface 136, and a rounded front surface 138. Said front end is also provided with a hole 140 for

receiving the laterally bent end 142 of the connecting rod 114', which projects downwardly therefrom through the adjustment 113 to the free end 101 of the switch arm 91, actuated by the solenoid coil 98. So that the upper end of the rod 114' may readily reciprocate, a suitable longitudinal slot 144 is provided in the shelf 146, projecting outwardly from the rear tip 34 of the extension 28. With this construction, when the warp end breaks, the solenoid 98 is actuated to raise the rod 114' to lift the hook 134 of the bar 130 above the upper surface 60 of the extensions 28, as shown in Figure 5, so that it will abut the end 20 of the filling motion rod 10 to stop the loom by pulling the upper end of the knock-off lever 42 forwardly, to actuate the connecting rod 48 and the respective brake and power levers 50 and 54. The loom is therefore knocked off on front centre, instead of rear centre, so that the inertia of the loom may be cut down so as to stop the loom at any desired portion of the rear centre portion of the fell 148 of the cloth, thereby eliminating any possibility of light or starting marks or cracky cloth.

If desired, suitable means, such as the adjusting grip 113 adapted to receive separate rod portions 114a' and 114b' of the connecting rod 114', is provided. Said grip 113 may comprise the two separate halves 150, each having two spaced transverse hemi-cylindrical channels near each end thereof adapted to be detachably secured together by the screw 154. It is obvious that by relative adjustment of the rod portions 114a' and 114b' in said grip 113 may the length of the rod 114' be suitably adjusted.

It is thus obvious that with my invention many of the parts of the prior art warp stop motion mechanism shown in Fig. 1 are eliminated, namely nineteen parts, including all bolts and nuts, and better results obtained by moving the magnetic switch to the front portion of the loom and attaching the hook bar 130 so that its front end will substantially overlie said magnetic switch, thereby only requiring the moving of said already existing parts forward on the loom and the attaching of the hook bar 130 and a pivot pin 128 for the hook bar 130 on the knock-off lever 42.

It is apparent that when the magnetic switch functions to raise the hook 134 across the path of the depending tip 20 of the filling rod 10 that said filling rod will abut said hook as it approaches the front centre position of the stroke of the lay to cause the hook 134 to move forwardly thereby tilting the knock-off lever 42 to actuate the rod 48 to actuate the loom stop mechanism in exactly similar fashion as actuated by the mechanical side filling stop motion.

It is also apparent that due to the inertia of the lay, the lay will stop in its back centre position, eliminating any possibility of providing light or starting marks on the cloth or cracky cloth, and the necessity of any manipulation of the loom to avoid said stopping marks, thereby speeding up production of the loom and consequently lowering the cost of the woven cloth. With my various adjustments, it is possible to adjust the stoppage of the lay to any position of its forward stroke, preferably in the back centre portion.

It is apparent that by the addition of merely two parts in place of nineteen that I have provided a novel type of electric stop motion mechanism to be used in association with the already existing mechanical side filling stop motion mechanism employing many more additional parts of

said side filling stop motion mechanism than formerly, with the advantages explained above.

It is understood that my invention is not limited to the specific embodiment shown and that various deviations may be made therefrom without departing from the spirit and scope of the appended claims.

What I claim is:

1. In a loom having a frame having side walls, an oscillatable lay having a well centrally thereof, means to reciprocate a shuttle across said lay; a mechanical "side filling" stop motion, comprising a filling rod pivotally mounted on the lay extending from said well to adjacent a frame side wall, prongs projecting rearwardly from said rod within said well normally supported at a spaced distance from the bottom of the well by a filling thread laid on passage of the shuttle over the lay and an arm projecting downwardly and forwardly from said rod adjacent said frame side wall, a filling motion cam having a forwardly depending upper cam surface longitudinally adjustably mounted on said loom adjacent the frame side wall at substantially top center of the oscillating stroke of the lay, a knock-off lever vertically and longitudinally adjustably pivotally mounted on said loom adjacent said frame side wall adjacent the top center of the stroke of the lay, having an upper end having a rounded front wall and a flat rear wall tiltable forwardly by said filling rod arm on failure of the filling, means to stop said loom and a rod connecting said knock-off lever to said loom stopping means to stop the loom when the prongs drop to the bottom of the well due to the absence of a filling thread on the lay, and an electric warp stop motion comprising a bar having an upwardly projecting hook at the front end thereof having a flat rear surface, means to pivotally mount the rear end of said bar on the upper end of said knock-off lever, a magnetic switch comprising a solenoid coil having a magnetizable core and a pivotable switch arm having an inner end normally raised above the solenoid core mounted on said loom underneath the front end of said bar adjacent the hook thereof, means connecting said switch arm to the front end of said hook bar of a length to raise said bar hook across the path of the oscillating filling rod arm, a drop wire needle supported by each warp thread, a transverse supporting rod underlying said needles and normally insulated therefrom, an electric circuit connected to said solenoid coil and connectable through a needle and said connecting rod on dropping of a needle due to breakage of a warp thread to energize the solenoid to lower the inner end of said switch arm to raise said bar hook across the path of said filling rod arm to abut said arm to cause said hook to tilt said knock-off lever to actuate said loom stopping means on the front center portion of the stroke of the lay.

2. In a loom having a frame having side walls, an oscillatable lay having a well centrally thereof, means to reciprocate a shuttle across said lay; a mechanical "side filling" stop motion, comprising a filling rod pivotally mounted on the lay extending from said well to adjacent a frame side wall, prongs projecting rearwardly from said rod within said well normally supported at a spaced distance from the bottom of the well by a filling thread laid on passage of the shuttle over the lay and an arm projecting downwardly and forwardly from said rod adjacent said frame side wall, a filling motion cam having a forwardly depending upper cam surface longitudinally adjustably mounted on said loom adjacent the frame side wall at substantially top center of the oscillating stroke of the lay, a knock-off lever vertically and longitudinally adjustably pivotally mounted on said loom adjacent said frame side wall adjacent top center of the stroke of the lay, having an upper end having a rounded front wall and a flat rear wall tiltable forwardly by said filling rod arm on failure of the filling, means to stop said loom and a rod connecting said knock-off lever to said loom stopping means to stop the loom when the prongs drop to the bottom of the well due to the absence of a filling thread on the lay, and an electric warp stop motion comprising a bar having an upwardly projecting hook at the front end thereof having a flat rear surface,

surface mounted on said loom adjacent the frame side wall at substantially top center of the oscillating stroke of the lay, a knock-off lever pivotally mounted on said loom adjacent said frame side wall adjacent top center of the stroke of the lay, having an upper end having a rounded front wall and a flat rear wall tiltable forwardly by said filling rod arm on failure of the filling, means to stop said loom and a rod connecting said knock-off lever to said loom stopping means to stop the loom when the prongs drops to the bottom of the well due to the absence of a filling thread on the lay, and an electric warp stop motion comprising a bar having an upwardly projecting hook at the front end thereof having a flat rear surface, means to pivotally mount the rear end of said bar on the upper end of said knock-off lever, a magnetic switch comprising a solenoid coil having a magnetizable core and a pivotable switch arm having an inner end normally raised above the solenoid core mounted on said loom underneath the front end of said bar adjacent the hook thereof, means connecting said switch arm to the front end of said hook bar of a length to raise said bar hook across the path of the oscillating filling rod arm, a drop wire needle supported by each warp thread, a transverse supporting rod underlying said needles and normally insulated therefrom, an electric circuit connected to said solenoid coil and connectable through a needle and said connecting rod on dropping of a needle due to breakage of a warp thread to energize the solenoid to lower the inner end of said switch arm to raise said bar hook across the path of said filling rod arm to abut said arm to cause said hook to tilt said knock-off lever to actuate said loom stopping means on the front center portion of the stroke of the lay.

3. In a loom having a frame having side walls, an oscillatable lay having a well centrally thereof, means to reciprocate a shuttle across said lay; a mechanical "side filling" stop motion, comprising a filling rod pivotally mounted on the lay extending from said well to adjacent a frame side wall, prongs projecting rearwardly from said rod within said well normally supported at a spaced distance from the bottom of the well by a filling thread laid on passage of the shuttle over the lay and an arm projecting downwardly and forwardly from said rod adjacent said frame side wall, a filling motion cam having a forwardly depending upper cam surface longitudinally adjustably mounted on said loom adjacent the frame side wall at substantially top center of the oscillating stroke of the lay, a knock-off lever vertically and longitudinally adjustably pivotally mounted on said loom adjacent said frame side wall adjacent top center of the stroke of the lay, having an upper end having a rounded front wall and a flat rear wall tiltable forwardly by said filling rod arm on failure of the filling, means to stop said loom and a rod connecting said knock-off lever to said loom stopping means to stop the loom when the prongs drop to the bottom of the well due to the absence of a filling thread on the lay, and an electric warp stop motion comprising a bar having an upwardly projecting hook at the front end thereof having a flat rear surface, means to pivotally mount the rear end of said bar on the upper end of said knock-off lever, a magnetic switch comprising a solenoid coil, and a pivotable switch arm having an inner end normally raised above the solenoid core mounted on said loom, adjustable means connecting said sole-

noid arm to the front end of said bar to raise said bar hook across the bar of the oscillating filling rod arm, a drop wire needle supported by each warp thread, a transverse supporting rod underlying said needles and normally insulated therefrom, an electric circuit connected to said solenoid coil and connectable through a needle and said connecting rod on dropping of a needle due to breakage of a warp thread to energize the solenoid to lower the inner end of said switch arm to raise said bar hook across the path of said filling rod arm to abut said arm to cause said hook to tilt said knock-off lever to actuate said loom stopping means on the front center portion of the stroke of the lay.

4. In a loom having a frame having side walls, an oscillatable lay having a well centrally thereof and means to reciprocate a shuttle across said lay; a mechanical "side filling" stop motion, comprising a filling rod pivotally mounted on the lay extending from said well to adjacent a frame side wall, prongs projecting rearwardly from said rod within said well normally supported at a spaced distance from the bottom of the well by a filling thread laid on passage of the shuttle over the lay and an arm projecting downwardly and forwardly from said rod adjacent said frame side wall, a filling motion cam having a forwardly depending upper cam surface longitudinally adjustably mounted on said loom adjacent the frame side wall at substantially the center portion of the oscillating stroke of the lay, a knock-off lever vertically and longitudinally adjustably pivotally mounted on said loom adjacent said frame side wall adjacent the center portion of the stroke of the lay, having an upper end having a rounded front wall and a flat rear wall tilttable forwardly by said filling rod arm on failure of the filling, means to stop said loom and a rod connecting said knock-off lever to said loom stopping means to stop the loom when the prongs drop to the bottom of the well due to the absence of a filling thread on the lay, and an electric warp stop motion comprising a bar having an upwardly projecting hook at the front end thereof having a flat rear surface, means to pivotally mount the rear end of said bar on the upper end of said knock-off lever, a magnetic switch having a coil and a movable switch arm actuated by said coil mounted on said loom, adjustable means connecting said switch arm to the front end of said bar to raise said bar hook across the path of the oscillating filling rod arm, a drop wire needle supported by each warp thread, a transverse supporting rod underlying said needles and normally insulated therefrom, an electric circuit connected to said coil and connectable through a needle and said connecting rod on dropping of a needle due to breakage of a warp thread to raise said arm to raise said bar hook across the path of said filling rod arm to abut said arm to cause said hook to tilt said knock-off lever to actuate said loom stopping means on the front center portion of the stroke of the lay.

5. In a loom having a frame having side walls, an oscillatable lay having a well centrally thereof and means to reciprocate a shuttle across said lay; a mechanical "side filling" stop motion, comprising a filling rod pivotally mounted on the lay extending from said well to adjacent a frame side wall, prongs projecting rearwardly from said rod within said well normally supported at a spaced distance from the bottom of the well by a filling thread laid on passage of the shuttle over the lay and an arm projecting downwardly and for-

wardly from said rod adjacent said frame side wall, a filling motion cam having a forwardly depending upper cam surface mounted on said loom adjacent the frame side wall at substantially the center portion of the oscillating stroke of the lay, a knock-off lever pivotally mounted on said loom adjacent said frame side wall adjacent the center portion of the stroke of the lay, having an upper end having a rounded front wall and a flat rear wall tilttable forwardly by said filling rod arm on failure of the filling, means to stop said loom and a rod connecting said knock-off lever to said loom stopping means to stop the loom when the prongs drop to the bottom of the well due to the absence of a filling thread on the lay, and an electric warp stop motion comprising a bar having an upwardly projecting hook at the front end thereof having a flat rear surface, means to pivotally mount the rear end of said bar on the upper end of said knock-off lever, a magnetic switch having a coil and a movable switch arm actuated by said coil mounted on said loom, means connecting said switch arm to the front end of said bar to raise said bar hook across the path of the oscillating filling rod arm, a drop wire needle supported by each warp thread, a transverse supporting rod underlying said needles and normally insulated therefrom, an electric circuit connected to said coil and connectable through a needle and said connecting rod on dropping of a needle due to breakage of a warp thread to raise said arm to raise said bar hook across the path of said filling rod arm to abut said arm to cause said hook to tilt said knock-off lever to actuate said loom stopping means on the front center portion of the stroke of the lay.

6. In a loom having a frame having side walls, an oscillatable lay having a well centrally thereof, means to reciprocate a shuttle across said lay; a mechanical "side filling" stop motion, comprising a filling rod pivotally mounted on the lay extending from said well to adjacent a frame side wall, prongs projecting rearwardly from said rod within said well normally supported at a spaced distance from the bottom of the well by a filling thread laid on passage of the shuttle over the lay and an arm projecting downwardly and forwardly from said rod adjacent said frame side wall, a filling motion cam having a forwardly depending upper cam surface longitudinally adjustably mounted on said loom adjacent the frame side wall at substantially top center of the oscillating stroke of the lay, a knock-off lever vertically and longitudinally adjustably pivotally mounted on said loom adjacent said frame side wall adjacent top center of the stroke of the lay, having an upper end having a rounded front wall and a flat rear wall tilttable forwardly by said filling rod arm on failure of the filling, means to stop said loom and a rod connecting said knock-off lever to said loom stopping means to stop the loom when the prongs drop to the bottom of the well due to the absence of a filling thread on the lay, and an electric warp stop motion comprising a drop wire needle supported by each warp thread, a transverse supporting rod underlying said needles and normally insulated therefrom, a magnetic switch having a coil and a switch arm actuated by said coil mounted on said loom adjacent the lower portion of the side wall thereof adjacent the front portion of the stroke of the lay; an electric circuit connected to said coil and connectable through a needle and said connecting rod on dropping of a needle due to breakage of

a warp thread; a bar having an upwardly projecting hook at the front end thereof having a flat rear surface, means to pivotally mount the rear end of said bar on the upper end of said knock-off lever so that the front end of said bar substantially overlies said switch, adjustable means connecting said switch arm to the front end of said bar of a length on energization of said coil to raise said bar hook across the path of the oscillating filling rod arm to cause said arm to strike said hook to cause said bar to move said knock-off lever forwardly to actuate said loom stopping means on the front center portion of the stroke of the lay.

7. In a loom having a frame having side walls, an oscillatable lay having a well centrally thereof, means to reciprocate a shuttle across said lay; a mechanical "side filling" stop motion, comprising a filling rod pivotally mounted on the lay extending from said well to adjacent a frame side wall, prongs projecting rearwardly from said rod within said well normally supported at a spaced distance from the bottom of the well by a filling thread laid on passage of the shuttle over the lay and an arm projecting downwardly and forwardly from said rod adjacent said frame side wall, a filling motion cam having a forwardly depending upper cam surface mounted on said loom adjacent the frame side wall at substantially top center of the oscillating stroke of the lay, a knock-off lever pivotally mounted on said loom adjacent said frame side wall adjacent the top center of the stroke of the lay, having an upper end having a rounded front wall and a flat rear wall tilt-able forwardly by said filling rod arm on failure of the filling, means to stop said loom and a rod connecting said knock-off lever to said loom stopping means to stop the loom when the prongs drop to the bottom of the well due to the absence of a filling thread on the lay, and an electric warp stop motion comprising a drop wire needle supported by each warp thread, a transverse supporting rod underlying said needles and normally insulated therefrom, a magnetic switch having a coil and a switch arm actuated by said coil mounted on said loom; an electric circuit connected to said coil and connectable through a needle and said connecting rod on dropping of a needle due to breakage of a warp thread; a bar having an

upwardly projecting hook at the front end thereof having a flat rear surface, means to pivotally mount the rear end of said bar on the upper end of said knock-off lever, means connecting said switch arm to the front end of said bar on energization of said coil to raise said bar hook across the path of the oscillating filling rod arm to cause said arm to strike said hook to cause said bar to move said knock-off lever forwardly to actuate said loom stopping means on the front center portion of the stroke of the lay.

8. In a loom having a frame having side walls, an oscillatable lay, means to reciprocate a shuttle across said lay and loom stopping means; in combination, a mechanical "side filling" stop motion having an oscillatable filling rod arm, and a knock-off lever abuttable by said arm on failure of filling on said lay to actuate the loom stopping means and an electric warp stop motion, comprising a magnetic switch, drop wire needles and an electric circuit actuated on dropping of a needle to actuate said switch; and a bar having an upwardly projecting hook at the front end thereof, having a flat rear surface, means to pivotally mount the rear end of said bar on the upper end of said knock-off lever and means connecting said switch to the front end of said bar of a length to raise said bar hook above the normal path of the top of the knock-off lever and across the path of the oscillating filling rod arm to cause said filling rod arm to abut said hook to tilt said knock-off lever to actuate said loom stopping means on the front center portion of the stroke of the lay.

35 SAMUEL W. LA ROCQUE.
